UNITED STATES PATENT OFFICE.

BERNARD JACQUART, OF SOUTH RIVER, NEW JERSEY, AND JOHN V. V. BOORAEM,
OF NEW YORK, N. Y.

CLAY-CLEANER.

1,089,840.

Specification of Letters Patent. Patented Mar. 10, 1914.

Application filed October 25, 1912. Serial No. 727,665.

To all whom it may concern:

Be it known that we, BERNARD JACQUART and JOHN V. V. BOORAEM, both citizens of the United States, and residents, 5 respectively, of South River, in the county of Middlesex and State of New Jersey, and the city of New York, borough of Brooklyn, in the county of Kings and State of New York, have invented certain new and useful 10 Improvements in Clay-Cleaners, of which the following is a specification.

This invention relates to clay cleaners, and more particularly to improvements in knives used in such clay cleaners, and the object of 15 the invention is to provide an improved knife, which might be readily adjusted in position, and readily removed for repairing and cleaning and sharpening.

A further object is to provide means for 20 properly adjusting the knife.

In the use of knives in clay cleaners it very often happens that a space between the knife and the support for the clay to be cut, is filled with small pebbles, which so clog 25 the space as to render the knife useless in a large degree, and it also happens that the extreme wear and tear to which the knives are subjected requires much repairing, and sharpening and readjustment; and a further 30 necessity is to have the knives in parallelism with the support for the clay so as to make an equal cut of the clay, and prevent thereby the knife from being subjected to breaking. The securing of the knives in exact position 35 is quite important, and additional means for adjustment of the knives have, for this reason, been provided.

Our invention further consists in providing knives for clay cleaners with adjustment 40 of the knife in respect to this plate and in adjustment with the plates themselves, and at the same time providing means for enabling the knife with its plate to be turned in position to permit this fine adjustment.

45 In the accompanying drawings, Figure 1 is a plan view of one of the improved knives for clay cleaners, Fig. 2 is a plan view of the same, with the knife turned over bottom up, Fig. 3 is a side view of the knife, Fig. 4 is a vertical transverse section of the rotary plate of the clay cleaner with the knives in position ready to cut, Fig. 5 is an end view of a portion of the plate showing the position of the knife, and Fig. 6 is a side view 55 of the tripper arrangement.

Similar characters of reference indicate corresponding parts of the various views.

Referring to the drawings, and more particularly to Fig. 4, a rotary knife carrier 10 of the clay cleaner is provided with a wearing plate 11, which is secured to the plate by suitable screws 12. The plates 11 are provided with openings 13, as are well known in the art, in which openings pivoted knife supports 14 are arranged, which knife supports have pivoted shafts at each end thereof, which engage bearings 16 of the carrier 10. A bolt 9 holds the parts in position. These shafts permit the knife supports 14 to be swung to the position shown in Fig. 2, 70 bottom upward, to enable the knives 16¹ to be adjusted in position. The knives are provided with slots 17, which form guideways for the fastening screws 18, which hold the knives against the knife supports 14, by 75 the aid of a fastening plate 19, held in position against the knife supports by the screws 18. The fastening plates 19 are provided at their rear end with shoulders 20 to take up the thickness of the knife 16, the said fastening plates capable of being used on either side. The knife 16¹ projects somewhat beyond the knife supports 14, and is distant 80 from the wearing-plate 25 a suitable distance, to allow the cut off clay to pass therebetween. The tripper wearing plate 25 is made of suitable wearing material, similar to the wearing plate 11, and is secured to the tripper 26 by means of screws 27. These 85 trippers are pivoted at 28 and are provided with extensions 29 connected by a link 30, which is in turn secured to a spring 31, secured to the plate 10. An extension 29 is provided with an arm 32, which has a detachable striking plate 33, which may be 90 struck by a roller 34, supported on a stationary plate 35 pivoted at 36 to the frame 37 of the machine. A second roller 38 eccentrically pivoted at 39 is operated by a lever 40 with an engaging device 41. The 100 object of the operation of the lever 40, and eccentric rollers 38 is to place the rollers 34 into operative position, with the wearing plate 33, or in inoperative position therewith. When the roller 34 is in operative position, the rotating plate 33 strikes against the roller 34, and thereby operates the 105 trippers around their pivots 28 in the direction of the knives, and thereby causes any clogging between the trippers 26 and the knives 110

to be removed. To control the movement of the extensions 29 adjustable bolts 42 engaging the carrier 10 are provided. To further insure the adjustment of the knives, the 5 knife carriers 14 are provided with downwardly extending members 50, which are engaged by a screw-threaded pin 51, which is adjustable on the extension 50, and held in position by the jam nut 52. These pins are 10 arranged as shown in Fig. 2, and they permit the adjustment of the pivoted knife carrier in relation to the rotary carrier 10, while the screws 18 permit the adjustment of the fastening plates 19, and permit the 15 adjustment of the knives in proper position. The pivoted supports of the knife carriers permit the turning over of the carriers bottom upward, to enable the knives to be removed for repairing and sharpening.

20 We have shown an embodiment of our invention, but it is clear that changes may be made therein without departing from the spirit of the invention.

We claim:

25 1. An improved knife for clay cleaners comprising a carrier, pivoted shafts at each end thereof, a knife plate supported on the carrier and having shoulders of knife-thickness at its rear-edge, a knife between the carrier and the knife-plate, and means for ad-

30

justing the knife on the carrier radially in and out from the axis of the carrier.

2. An improved knife for clay cleaners, comprising a reversible pivoted carrier, a knife radially adjustably secured thereto, 35 and a set-screw at the lower portion of the knife carrier for changing its position.

3. A knife for clay cleaners comprising a carrier, having unobstructed movement into reverse position of the knife, a knife fastening plate at the lower side thereof, a knife between the carrier and fastening plate, means adjustably holding the fastening plate and knife in position, and means for varying the position of the knife carrier with the 40 knife thereon arranged to permit free movement of the knife carrier with its knife, from its normal position to a position with the bottom side up.

In testimony, that we claim the foregoing 50 as our invention, we have signed our names in presence of two subscribing witnesses.
